GLASS ROLLING MEANS

Yvon Brancart, Ronquieres, Belgium

Application July 28, 1932, Serial No. 625,273
In Germany August 7, 1931

3 Claims. (Cl. 49—34)

This invention relates to the manufacture of plate-glass and like glass plates, having a surface free from waves or undulations.

To obviate the formation in the surface of plate-glass of waves due, more particularly, to unequal contraction of the two sides of the plate it has been proposed to roll the glass shortly after casting the same and whilst still plastic upon the table, with an impressing roller adapted to form in the surface thereof slight depressions and projections which the heat contained within said metal causes ultimately to subside and to disappear. It has likewise been proposed to roll glass with a roller having a higher circumferential speed than if it were merely rolling over the glass.

It has been found however, that glass wholly free from waves cannot always be obtained by such means. My invention is based upon observation of the fact that, in known processes, waves are formed in the surface of the glass owing to the roller being jerked by the gears of its driving mechanism, for instance when the well-known rack mechanism is used, or by said roller grinding and chattering upon the surface when driven thereover at a circumferential speed greater than if it were merely rolling thereupon. Said grinding and chattering arise even when the roller is continuously driven, as through a cable, a chain or helical gearing, for example.

According to my invention, to remove the causes of said superficial waves I use an impressing roller driven at a circumferential speed slightly greater than would result if it were merely rolled over the glass, and I provide said roller with trunnions so supported above the casting table that the table does not contact directly with the roller or with said trunnions. The impressing roller thus is enabled to act on the glass with perfect uniformity.

To support the roller trunnions I may use bearings, similar to some bearings for calibrating rollers for example, having casters adapted to rest and travel upon the edges of the casting table. I thus obtain a perfectly uniform action of the impressing roller, ensuring the subsequent disappearance of the marks temporarily made thereby in the glass and resulting in an even surface which requires no reduction by grinding or smoothing.

My invention therefore likewise extends to apparatus comprising an impressing roller, a casting table, a continuously driven transmission adapted to rotate said roller at circumferential speed greater than if said roller were merely

rolled over the table, trunnions at the ends of said roller, and bearings adapted to support said trunnions, said bearings being provided with casters adapted to rest and travel upon the edges of the casting table or upon tracks integral therewith.

In one constructional embodiment of my invention, the casting table may be movable relatively to the roller, said roller being driven by a cable wound round the same or passing over a pulley integral therewith and each end of said cable being secured to one end of said movable table. The roller may then be rotated by means of the traversing motion of the table itself.

In the accompanying drawing, illustrating diagrammatically and by way of example two constructional embodiments of my invention wherein transmission is by cable,

Fig. 1 is a side view of a glass-rolling apparatus wherein the casting table is movable relatively to the printing roller, and

Fig. 2 illustrates my invention as applied to a case wherein a movable roller traverses over a stationary casting table.

In the figures, 1 is the casting table and 2 the rough faced impressing roller whereof the trunnions 2' are supported in any convenient manner at an appropriate distance above said table, as by bearings 10 resting upon the edges of casting table 1 through casters 11, for example.

In the embodiment illustrated in Fig. 1, the table 1 moves along a rolling track 3 and thus carries beneath roller 2 the mass of glass which said roller is to spread into the form of a plate whilst imprinting therein the striae or other patterns adapted to obviate in a known manner the formation of longitudinal waves in the surface thereof. To fulfil this dual function the roller must revolve around its longitudinal axis, and it is so rotated by means of a cable 4, wound round a pulley 5 keyed to the roller and having either end secured to the corresponding end of casting table 1. It will be obvious that when table 1 is caused to move in the direction of the arrow *a* the roller 2 will revolve continuously in the direction of the arrow *b*, that the method whereby trunnions 2' are supported and the cable is wound continuously round pulley 5 will obviate all jerks in the rotation of the roller, and that no transverse undulations or waves can be formed in the surface of the glass plate undergoing rolling.

In the alternative embodiment of my invention illustrated in Fig. 2 the casting table is stationary, and roller 2 must therefore be moved rela-

tively to the same whilst being rotated. Roller 2 is rotated by means of an endless cable 6 wound round pulley 5, integral with the roller, and round two end pulleys 7 and 8 whereof one or other is driven, and it is moved relatively to the casting table by means of a stationary cable 9 whereof a loop is likewise wound round pulley 5. Whilst being revolved by the pull of cable 6, as indicated by arrows c, d, the roller winds itself 10 along the stationary cable and progresses in the direction of arrow e.

Conversely, roller 2 might be traversed relatively to the casting table by means of the endless cable 6 and be rotated by means of stationary cable 9 if cable 6 were, for example, secured to one of the bearings of the roller to drag the latter along the table by direct traction, instead of being wound round pulley 5. Other constructional embodiments or combinations of members 20 might likewise be adopted.

By an appropriate selection of the diameter of pulley 5 relatively to that of roller 1 the circumferential speed of the latter may be accurately adjusted to be slightly greater than if it rolled 25 in contact with the casting table, so that said roller slightly drives the glass towards the forward end of the cast plate whilst revolving.

My invention is not of course limited to the use of cables or belts for transmitting motion 30 to the impressing roller. Without departure from the scope of the invention, said roller might be traversed over the casting table by means of a worm and nut or by hydraulic plungers, and be rotated by means of a worm and wheel or by helical 35 gears. Said transmission members adapted to provide continuous drive may be combined in a great number of ways which are too well-known per se to require any description in detail, my invention only being limited in regard to principle and scope by its main features, 40 as set forth in the following claims.

I claim:

1. Apparatus for rolling and imparting a finished smooth surface to plate-glass and glass plates, comprising the combination, with a casting table, of a rough roller having unequal portions on the peripheral rolling surface thereof and supported above said table in spaced relation thereto, there being trunnions at the ends of 50 the roller, a pulley rigidly associated with said roller and having a relatively smaller diameter than the same, bearings carrying said trunnions and resting upon the longitudinal edges of the table, means for causing relative motion between 55 said bearings and said table, and a continuous and smoothly operating gearless transmission means cooperating with said pulley and thereby

smoothly and uniformly revolving said roller in order to cause the same to smoothly traverse the glass upon said table and temporarily impart slight depressions and projections to the surface of said glass in order to finally produce a smooth condition thereof which is free from waves and other superficial flaws. 80

2. Apparatus for rolling and imparting a finished smooth surface to plate-glass and glass plates, comprising the combination, with a casting table, of a rough roller having unequal portions on the peripheral rolling surface thereof and rotatably supported above said table in spaced relation thereto, means for causing relative movement between said roller and said table, and smoothly and continuously operating gearless transmission means uniformly rotating said roller at a noticeably greater speed than would result from normal traction of the roller upon the surface of the glass in order to cause said roller to smoothly traverse said glass and temporarily impart slight depressions and projections to the same in order to finally produce a smooth condition thereof which is free from waves and other superficial flaws. 90

3. Apparatus for rolling and imparting a finished smooth surface to plate-glass and glass plates, comprising the combination, with a casting table and a rolling track to support the table, of a rotatable rough roller spaced in stationary position above said table and having unequal portions upon the peripheral rolling surface thereof, there being trunnions at the ends of the roller, a pulley rigidly associated with said roller and having a relatively smaller diameter 105 than the same, bearings carrying said trunnions, casters supporting said bearings and resting upon the longitudinal edges of the table, a smoothly and continuously operating means in the form of a flexible transmission member wound around 110 said pulley and secured at each end to a corresponding end of said table, and means for moving said table beneath said roller in order to move the glass on the table with respect to the roller and simultaneously rotate said pulley by 120 means of said flexible transmission member and thereby uniformly rotate said roller at a noticeably greater speed than would result from normal traction of the roller upon the surface of the glass, for the purpose of causing said roller to 125 smoothly traverse said glass on said table, relatively speaking, and temporarily impart slight depressions and projections to the same in order to finally produce a smooth condition thereof which is free from waves and other superficial 130 flaws. 115

YVON BRANCART.
